UNITED STATES PATENT OFFICE.

ERNEST F. SYMONDS AND GEORGE W. BRANN, OF SALEM, MASSACHUSETTS, ASSIGNORS, BY DIRECT AND MESNE ASSIGNMENTS, TO STANDARD MACHINES COMPANY, OF BOSTON, MASSACHUSETTS, A CORPORATION OF MAINE.

SHOE-POLISHING MACHINE.

No. 910,740.

Specification of Letters Patent.

Patented Jan. 26, 1909.

Application filed November 9, 1906. Serial No. 342,728.

To all whom it may concern:

Be it known that we, ERNEST F. SYMONDS and GEORGE W. BRANN, citizens of the United States, and residents of Salem, Essex county, Massachusetts, have invented certain new and useful Improvements in Shoe-Polishing Machines, of which the following is a specification.

The invention relates to a machine for automatically polishing or shining shoes and has for its object to provide a simple and efficient construction by which the blacking or polish may be quickly and conveniently applied to the shoe and then the shoe subjected to a rubbing or polishing action.

In practicing the invention the brushes which are utilized to apply the polish to the shoe and to subject the surface to which the polish has been applied to a rubbing action, are mounted within a casing in such manner that they are inaccessible. The brushes and the mechanism for operating them and controlling their action is driven by an electric or other suitable motor which may be thrown into operation by the user either by the introduction of a coin or in any other suitable or desired manner. When the motor is started by the user motion is imparted to the brushes and at the same time the brushes are rendered accessible to the user either by a movement of the brushes or by the movement of parts which protect and render them inaccessible. The brushes are so mounted and arranged that when they are thus rendered accessible the rubbing surfaces of the brushes are in convenient position for the user to apply his foot thereto. The user then applies his foot to the brush which acts to apply the polish or blacking, manipulating his foot so that all parts of the surface of the shoe to which it is desired to apply the polish are brought into contact with the rubbing surface of the brush. After the blacking has been thus applied to the shoe the user applies his foot in a similar manner to the surface of the polishing brush bringing all parts of the surface to which polish has been applied into contact with the rubbing surface of the brush so that the surface is thoroughly rubbed and the polishing of the shoe completed.

The brushes when rendered accessible and presented in position for the application of the foot thereto are maintained in this position for a definite period of time which should

be sufficient for the user to apply the polish to the shoe and thoroughly rub the surface to which the polish has been applied. After the brushes have remained accessible for the predetermined time they are rendered inaccessible either by withdrawing them within casing or by the movement of some part which covers and protects them. At the same time the motor which operates the brushes and the mechanism for controlling them is stopped and remains at rest until again started into motion by the user.

In order that the user may know when the brushes have remained in an accessible position for a definite part of the period during which they are to remain accessible and may thus apply the foot to the polishing brush in time to secure a thorough rubbing of the surface to be polished, an indicator is provided which is operated during the period when the brushes are accessible and which indicates that a certain proportion of this period has elapsed.

The various features of the invention may be embodied in machines which are started into operation in any suitable manner and may be used with especial advantage in machines which are provided with devices by which the operating motor is started by the introduction of a coin. The polish applying and rubbing brushes may be rendered accessible and inaccessible in any suitable manner but it is preferred in practicing the invention to so mount these brushes within the casing of the machine that they are normally withdrawn within the casing where they are inaccessible and are rendered accessible by projecting them through an opening or openings in the casing so that their rubbing surfaces are presented in convenient position for the application of the foot thereto.

The various features of the invention will be set forth in the claims and will be readily understood from the following detailed description of the machine shown in the accompanying drawings which embodies the various features of the invention in the forms in which we prefer to employ them.

In these drawings Figure 1 is a partial rear elevation of the machine with the casing broken away to show the interior mechanism; Fig. 2 is a sectional view on line 5—5 Fig. 1; Figs. 3 and 4 are details of mechanism to be hereinafter described; Fig. 5 is a sectional

elevation showing the devices for starting and stopping the driving motor; Fig. 6 is a detail showing the devices for projecting and withdrawing the brushes and Fig. 7 is a detail of the coin operated latch for starting the motor.

In the machine shown in the accompanying drawings the various parts of the operating mechanism are inclosed within a casing 10 which completely incloses the mechanisms and protects them from injury or misuse. In this machine the various mechanisms and parts are operated by an electric motor 2 mounted in the upper part of the casing and 15 connected through conductors with any suitable source of electrical supply. The conductors lead to two contacts 5 which are arranged to engage contacts 6 and 11 secured to a support within the casing.

20 The conductor 9 leads from contact 11 to the motor 2 and conductor 10 leads from the motor to the devices by which the motor circuit is completed and broken in starting and stopping the motor.

25 The devices for controlling the operation of the motor are best shown in Figs. 1 and 5. As shown in these views the conductor 10 is connected with a contact 12 mounted upon an insulating block 13. The contact 6 is connected through a wire 14 with a co-operating contact in the form of a lever 15 pivoted at 16 to an insulating block 17. Under normal conditions the contact lever 15 is held out of engagement with the contact 12 by means of 30 a latch arm 18 which engages the lower end of the lever and holds it in position against the tension of the spring 19. The latch arm 18 is carried by a plate 20 which is pivoted at 21 and is provided at its forward end with a 35 ledge 22 arranged below a coin chute 23. Directly in the rear of the ledge 22 is an opening 24 in the plate 20 which overlies a chute 25. The plate 20 is provided with guard flanges 26, 26' for insuring the engagement of 40 the coin with the ledge 22 as the coin falls out of the lower end of the coin chute 23. The guard flange 26 is inclined toward the opening 24 and acts to deflect the coin through 45 the opening 24 after the coin has struck the 50 ledge 22.

The plate 20 with its connected latch arm 18 is held in normal position with the latch arm in front of the contact lever 15 as indicated in Fig. 5 by a light spring 27. The 55 coin chute 23 is provided with an extension 23' the lower end of which registers with the upper end of the chute 23 and the upper end of which registers with a recess 23^a formed in a block 23^b secured in the upper part of the 60 casing. The recess 23^a communicates with a coin slot 23^c through which a coin may be introduced into the machine.

When a coin is introduced into the slot 23^c it falls down onto the ledge 23^d and rolls over 65 the end of a permanent magnet 23^e. The

momentum of the coin carries it across a discharge opening 23^f and into the discharge passage 23^g which registers with the upper end of the chute 23'. If a blank slug of iron or other magnetic metal is introduced it will 70 roll across the end of the magnet 23^e and will follow the surface of the magnet falling down through the discharge opening 23^f.

When the coin passes down through the coin chute 23' and chute 23 it strikes upon 75 the ledge 22 causing the latch plate 20 to swing downward against the tension of its spring so that the contact lever 15 is swung toward the left in Fig. 5 by its spring 19, the lower end of the contact lever passing above 80 the latch arm 18 so that the latch plate 20 and latch arm 18 are held in their depressed position. The coin immediately passes off of the ledge 22 and falls through the opening 24 into the chute 25 by which it is directed 85 into a coin receptacle 28.

When the contact lever 15 swings toward the left in Fig. 5 it passes between the contact plates 12 thus completing the electric circuit for the motor and starting the motor. 90 The motor will now continue in action until the contact lever 15 is swung toward the right in Fig. 8 to disengage it from the contact 12 when the motor will stop. This movement of the contact lever 15 will carry 95 its lower end from above the latch arm 18 so that the latch plate 20 and arm 18 may swing up into the position indicated in Fig. 5 where the latch arm will act to hold the contact lever out of engagement with the contact 12 100 until another coin is introduced. The devices for operating the contact lever 15 to thus stop the motor and reset the devices for starting the motor will be described hereinafter.

The motor is connected with and drives a 105 shaft 29 through a series of belts 30 which pass over a pulley on the motor shaft and a pulley 31 secured to the shaft 29. The polish applying and rubbing brushes and the devices for rendering the brushes accessible and 110 inaccessible are driven from this shaft 29.

In the machine being described the polish applying and rubbing brushes consist of rotary brushes 32 and 33 which are mounted upon a shaft 35 driven from the shaft 29 115 through a chain 36 passing over sprocket wheels 37 and 38 secured to the shafts 29 and 35 respectively. The shaft 35 is supported in a frame 39 which is provided with arms 40 by which the frame is suspended from the 120 shaft 29.

The parts are so arranged that normally the frame 39 is maintained in such position that the brushes 32 and 33 are withdrawn within the casing as indicated in Fig. 5 where 125 they are inaccessible. The brushes are rendered accessible and are presented in position for the convenient application of the foot of the user thereto by swinging the frame 39 forward so that the peripheries of 130

the brushes are projected through openings formed in the front of the casing in position to register with the brushes. When the frame 39 is thus projected as indicated in 5 dotted lines in Fig. 2 the bearings 41 for the shaft 35 engage recesses 42 formed in webs 43 which extend inward from the sides of the openings through which the brushes are projected. The bottoms of these recesses 42 10 form stops for determining the outer position of the frame and brushes and during the time that the brushes are accessible the frame is maintained in position against these stops 42.

The mechanism for swinging the frame 15 forward to project the brushes through the openings in the casing and for maintaining the brushes in this position during a definite period of time and then withdrawing the 20 brushes within the casing where they are in- accessible, is shown in Figs. 1-4 and in Fig. 9.

The swinging movements of the frame 39 are imparted thereto through a toggle lever comprising the toggle links 44 and 45. 25 The link 44 is pivoted to the frame 39 at 46 and to the link 45 at 47. The rear end of the link 45 is pivoted at 48 to the upper end of a lever 49. This lever is pivoted to a fixed support at 50 and the lower end of the lever is 30 forced against a stop 51 by a spring 52 the tension of which may be adjusted by a bolt 53 which supports one end of the spring. When the frame 39 is in its retracted position the outer end of the link 45 rests against 35 a stop pin 54 which thus determines the inward position of the frame and brushes. The toggle lever is connected by means of a link 55 with a crank arm 56 which is secured to the outer end of a shaft 57. The shaft 57 is 40 journaled in a support 58 and its inner end is supported and journaled on the end of a stud 59 secured to said support. This crank shaft is rotated through a half revolution to straighten the toggle levers and thus project 45 the brushes into accessible position and is then disconnected from the driving device through which it is operated. After a pre-determined time has elapsed the crank shaft is reconnected to its driver and is turned 50 through a half revolution to break the toggle lever and withdraw the brushes within the casing and then the motor is stopped thus stopping the driver for the crank shaft.

The driver for driving the crank shaft 57 55 consists of a worm wheel 60 mounted upon the stud 59 and driven from the shaft 29 through a worm 61 secured to a vertical shaft 62 which is connected with the shaft 29 by spiral gears 63.

60 The devices for intermittently connecting the worm wheel 60 with the shaft 57 comprise a pawl 64 which is pivoted to a disk 65 secured to or formed on the hub of the worm wheel 60. This pawl is arranged to engage 65 a shoulder 66 formed on a disk or flange 67

which is secured to or formed on the end of the shaft 57 adjacent to the disk 65. The flange 67 is provided with a second shoulder 68 arranged to be engaged by a spring operated pawl 69 pivoted to the disk 65. 70

When the parts are in normal or inactive position the disk 65 and pawl 64 are in the position indicated in Fig. 3. When the motor 2 is started by the introduction of a coin or otherwise, the worm wheel 60 and 75 disk 65 rotate in the direction of the arrow Fig. 3. The motion of the disk 65 is transmitted to the shaft 57 by reason of the engagement of the pawl 64 with the shoulder 66 of the flange 67 which is secured to the 80 shaft 57. As the shaft 57 rotates the crank 56 is moved from the position indicated in full lines Fig. 6 to the dotted line position *a* indicated in this figure. During this movement of the crank the toggle links are 85 straightened, thus swinging the frame 39 forward and bringing the bearings 41 of the frame against the stops 42. When the forward movement of the frame is arrested by the engagement of the frame with the stops 90 42, the continued straightening movement of the toggles causes the upper end of the lever 49 to yield. As the pivot 47 between the links of the toggle lever passes the line of centers the spring 52 acting on the lever 49 tends to 95 force the rear pivot 48 of the link 49 forward and to move the toggle links into the dotted line position shown at *b* Fig. 6. This pressure or force applied to the toggle links is transmitted to the crank 56 through the link 100 55 and tends to rotate the shaft 57 and connected disk 67 in the direction of the arrows Figs. 3 and 4. This force tending to rotate the shaft 57 presses the disk 67 forward against the pawl 69 which pawl acts to prevent 105 the forward rotation of the shaft 57 except as such movement is permitted by the rotation of the worm wheel 60. When the toggle is moved into such position that the spring 52 tends to advance the shaft 57, the 110 pressure between the pawl 64 and the shoulder 66 is relieved so that the pawl 64 is free to fall away from the shoulder as the pawl comes into the position shown in Fig. 4. The pawl is so pivoted that the weight of the pawl 115 tends to cause it to swing down into the position indicated in Fig. 4 as it passes under the shaft 57 and stud 59, the pawl being supported by its engagement with a pin 70 projecting from the disk 65. When the shaft 57 120 has made substantially a half revolution or has come into dotted line position *b* (Fig. 6) further upward movement of the toggle links is prevented and the links act to lock the frame in position against the stops 42. 125 The worm wheel 60 will now rotate idly upon the stud 59, the pawl 64 dropping away from the flange 67 as it passes around the lower half of said flange and the pawl 69 riding idly over the periphery of the flange as the 130

worm wheel is rotated. The idle rotation of the worm wheel will continue until the pawl 64 as it passes around the flange 67 is moved into position to engage the shoulder 66 on the flange. The pawl 64 is thus moved to reconnect the crank shaft 57 with the driving worm wheel 60 by means of a timing mechanism shown in Figs. 1 and 2.

In the construction shown the timing mechanism comprises a cam 71 (Figs. 3 and 4) arranged to be brought intermittently into position to move the pawl 64 into engagement with the shoulder 66 on the flange 67. This cam is secured to a shaft 72 to which is secured a star wheel 73. The star wheel is held yieldingly against rotation by a retaining spring 74 arranged to engage two adjacent points of the wheel. (Fig. 2) The star wheel is advanced intermittently by means of a pin 75 projecting from the worm wheel 60 and arranged to act successively upon the points of the star wheel. In the construction shown the star wheel is provided with eight pins or arms and at each revolution of the star wheel the pin 75 engages one of the arms of the star wheel and advances the wheel and consequently the shaft 72 one-eighth of a revolution.

When the parts are in normal inactive position the cam 71 will be in the position indicated in Fig. 3 where it would act to raise the pawl 64 into position to engage the shoulder 66. When the worm wheel starts forward and during the first half revolution of the worm wheel the pin 75 will advance the star wheel one-eighth of a revolution bringing the cam 71 into the position indicated in Fig. 4. When in this position the cam is out of the path of the pawl 64 so that the pawl drops away from the shoulder 66 as the worm wheel completes a half revolution. As the worm wheel continues to rotate idly the pin 75 acts to advance the star wheel step by step until the worm wheel has made eight revolutions when the cam 71 will be brought into the position indicated in Fig. 3. Now when the pawl 64 passes around the lower half of the disk 67 it will ride against the cam 71 and be lifted into engagement with the shoulder 66 so that the shaft 57 will be connected with the worm wheel 60 and be rotated thereby.

When the crank shaft 57 is reconnected with the driving worm wheel 60 by the action of the cam 71 the movement of the crank 56 causes the toggle links to be forced downward until the pivot 47 passes the line of centers, the spring 52 yielding to allow this movement of the toggle links. When the toggle has been moved into this position the weight of the frame and parts carried thereby will tend to rotate the shaft 57 and the rapid rotation of the shaft is prevented by the engagement of the shoulder

68 with the pawl 69 so that the rotation of the shaft 57 is governed by the rotation of the worm wheel 60. As the parts come into the position indicated in full lines in Figs. 2 and 6 of the drawings the driving motor is stopped thus stopping the rotation of the driving worm wheel 60 when the parts connecting the worm wheel with the crank shaft will be in the position indicated in Fig. 3. Thus whenever the motor is started the brushes are projected into position where the user may apply his foot thereto, are locked in position for a definite period of time controlled by the timing mechanism, and are then retracted into position where they are inaccessible and remain in this position until the motor is again started.

For the purpose of indicating when a definite proportion of the period during which the brushes are in accessible position has elapsed, an indicator is provided. In the construction shown this indicator is in the form of a bell 76 which is operated to sound an alarm when one-half of the period during which the brushes are accessible has elapsed. The devices for thus operating the bell consist of an arm 77 projecting from the shaft 72 which carries the star wheel of the timing mechanism as indicated in Figs. 1 and 6. As the shaft 72 is revolved the arm 77 engages the lower end of a lever 78 which is pivoted on shaft 57 and carries the bell hammer 79 on its upper end. This lever 78 is normally held in position against a yielding stop 80 by a spring 81 (Fig. 6). When the arm 77 engages the lower end of the lever 78 the lever is swung about its pivot against the tension of the spring 81. When the timing shaft 72 has made a half revolution the arm 77 passes beyond the shoulder 82 on the lever 78 thus quickly releasing the lever so that it is snapped forward by its spring, thus causing the hammer 79 to strike a sharp blow upon the bell 76 warning the user that half of the period during which the brushes will remain accessible has elapsed.

The devices for stopping the motor and thus stopping the driving worm wheel 60 when the brushes have been retracted and the parts connecting the driving motor with the mechanism for retracting the brushes has been brought into the position indicated in Fig. 3 is shown in Fig. 5. As shown in this view one of the arms 40 of the frame 39 which carries the brushes, extends above the shaft 29 on which the frame is suspended and is provided with a rearwardly projecting plate 83. Pivoted to this plate is a latch arm 84 provided near its outer end with a recess 85 adapted to engage a pin 86 which projects from the contact lever 15. When the lower end of the frame 39 is swung forward to project the brushes into accessible position, the

latch arm 84 rides forward over a fixed supporting pin 88 until this pin enters a recess 87 in the lower edge of the latch arm. As the pin 88 enters this recess the latch arm is lowered so that it rides on the pin 86 of the contact lever, the recess 85 passing to the right of the pin 86 in Fig. 5. Now when the frame 39 is swung rearwardly to retract the brushes, the recess 85 engages the pin 86 and the upper end of the contact lever is turned toward the left in Fig. 5 thus disengaging the lever from the contacts 12. During this movement of the latch arm 84 the pin 88 acting against the cam surface of the recess 87 lifts the latch arm 84 so that the recess 85 in the latch arm disengages the pin 86 on the contact lever, leaving said lever free to be moved into engagement with the contact 12 when the motor is to be again started. After the motor circuit is broken the momentum of the parts brings them into the position indicated in full lines.

Any suitable means may be employed for supplying polish to one of the brushes and in the construction shown polish is supplied to the brush 32 by means of a polish carrying box 90 which partially surrounds the brush and may contain a polish in the form of a paste. The box 90 is supported upon an arm 91 which is pivoted at 92 to one of the arms 40 of the frame and is provided at its lower end with a rectangular frame 93. This frame is secured to the lower end of the arm 91 by means of a plate 94 attached to the upper end of the frame and provided with a vertical flange 95 secured to the arm. The polish carrying box 90 is removably secured within the frame 93 by means of a spring latch 96 arranged to engage the lower edge of the box 90 and a latch 97 arranged to engage the upper edge of the box Fig. 2. The upper edge of the box is provided with a lip 98 which lies between the latch 97 and the front edge of the plate forming the top of the frame 93, thus preventing the rearward displacement of the box. When the brush 32 is in its rearward position the periphery of the brush bears against the polish contained within the box 90 and as the brush starts to rotate a portion of the polish is transferred to the periphery of the brush. When the brush is carried forward the supporting frame for the box also swings forward a short distance. When the brush 32 is retracted the periphery of the brush engages the polish within the box 90 and as the brush moves into its retracted position the box is moved rearwardly into the position indicated in Fig. 2 where the weight of the box and the parts carried by the pivoted support therefor tend to press the polish within the box against the periphery of the brush.

The box may be removed for the purpose of renewing the polish therein by depressing

the latch 96, swinging the box about the periphery of the brush and removing it through a door in the side of the casing. After a new supply of polish has been inserted in the box the box may be readily and quickly reattached to its supporting frame.

While it is preferred to employ the specific construction and arrangement of parts shown and described, it will be understood that the invention is not limited to such specific construction and arrangement and that various modifications or changes may be made in the forms and arrangements of the various mechanisms and of the various parts without departing from the invention.

Without attempting to point out in detail the various forms in which the invention may be embodied, what we claim and desire to secure by Letters Patent is:—

1. A shoe shining machine, having, in combination, a brush, means for presenting said brush for a predetermined time in a permanent location where the user may by manipulation of his foot apply all parts of his shoe to the rubbing surface of the brush and for rendering the brush inaccessible after said predetermined time, and mechanism for operating the brush during the time that it is accessible.

2. A shoe shining machine, having, in combination, two brushes, means for applying polish to one brush, means for presenting said brush for a predetermined time in a permanent location where the user may by manipulation of his foot apply all parts of his shoe to the rubbing surface of either brush, and for rendering the brush inaccessible after said predetermined time.

3. A shoe shining machine, having, in combination, a casing provided with an opening, a brush normally inaccessible within the casing, means for presenting and holding said brush in said opening where the user may by manipulation of his foot bring all parts of his shoe against the rubbing surface of the brush, and for rendering said brush inaccessible after a predetermined time.

4. A shoe shining machine, having, in combination, a casing, two brushes normally inaccessible within the casing, means for applying polish to one of said brushes, means for projecting said brushes through the casing and holding them in a definite position where the user may by manipulation of his foot bring all parts of his shoe against the rubbing surface of either brush during the time that they are accessible, and for rendering said brushes inaccessible after a predetermined time.

5. A shoe shining machine, having, in combination, a casing provided with an opening, a brush normally inaccessible within the casing, means for projecting said brush through said opening and holding it in

fixed position whereby the user may by manipulation of his foot bring all parts of his shoe against the rubbing surface of the brush, and for rendering said brush inaccessible after a predetermined time.

6. A shoe shining machine, having, in combination, a single polish applying brush, a single polishing brush, a casing within which said brushes are mounted, mechanism for projecting said brushes through the casing and maintaining them in fixed position for a predetermined time, whereby the user may by manipulation of his foot apply all parts of his shoe to the rubbing surface of either brush, and for withdrawing said brushes within the casing after said predetermined time.

7. A shoe shining machine, having, in combination, a casing, a polish applying brush, a polishing brush, mechanism for advancing and retracting the brushes to project their rubbing surfaces beyond the casing, maintain them in fixed position for a predetermined period, and then withdraw them within the casing, and mechanism for operating the brushes while in projected position.

8. A shoe shining machine, having, in combination, a casing, a brush, mechanism for projecting the brush into and holding it in a permanent location beyond the casing where the user may by manipulation of his foot apply all parts of his shoe to the rubbing surface of the brush during the time that it is accessible, and for withdrawing the brush within the casing after a predetermined time.

9. A shoe shining machine, having, in combination, a casing, two brushes, means for applying polish to one of the brushes, mechanism for projecting the brushes through the casing and holding them in fixed position where the user may by manipulation of his foot apply all parts of his shoe to the rubbing surface of either brush, and for withdrawing the brushes within the casing after a predetermined time.

10. A shoe shining machine, having, in combination, a frame, rotary brushes journaled in the frame, a casing provided with openings registering with the brushes, mechanism for advancing the frame and locking it in position with the peripheries of the brushes projecting through the openings where the user may by manipulation of his foot apply all parts of his shoe to the rubbing surface of either brush, and for retracting the frame after a predetermined time.

11. A shoe shining machine having in combination a rotary shaft, a frame mounted to swing about the axis of the shaft, brushes journaled in the frame and driven from the shaft, a casing having openings registering with the brushes, mechanism for advancing the frame and locking it in position with the peripheries of the brushes exposed, and mech-

anism for retracting the frame after a predetermined period.

12. A shoe shining machine, having in combination brushes, a casing, a motor, mechanism for driving the brushes from the motor, mechanism for advancing and retracting the brushes to project their rubbing surfaces beyond the casing and to withdraw them within the casing, means for coupling said mechanism with the motor, a timing mechanism for controlling the coupling of said mechanism with the motor to withdraw the brushes within the casing, and means for starting and stopping the motor.

13. A shoe shining machine having in combination brushes, a casing, mechanism for advancing and retracting said brushes to project their rubbing surfaces beyond the casing and to withdraw them within the casing, a driver for operating said mechanism, means for disconnecting the driver when the brushes are projected, and a timing mechanism for reconnecting said driver.

14. A shoe shining machine having in combination brushes, a casing, mechanism for advancing and retracting said brushes to project their rubbing surfaces beyond the casing and to withdraw them within the casing, a driver for operating said mechanism, means for disconnecting the driver when the brushes are projected, a timing mechanism for reconnecting said driver, and means for stopping the driver when the brushes are retracted.

15. A shoe shining machine having in combination brushes, a casing, means for presenting said brushes in position where they are accessible to the foot of the user, and for rendering said brushes inaccessible, a driver for operating said means, means for disconnecting the driver when the brushes are accessible, and a timing mechanism for reconnecting said driver.

16. A shoe shining machine having in combination a brush carrying frame, a brush mounted therein, a casing provided with an opening registering with the brush, a toggle lever for moving said frame to project the brush through the opening and lock it in position, and mechanism for operating the toggle.

17. A shoe shining machine having in combination a brush carrying frame, a brush mounted therein, a spring toggle connected with the frame, a stop against which the frame is forced by the straightening of the toggle and mechanism for straightening and breaking the toggle.

18. A shoe shining machine, having in combination a polish applying brush, mechanism for advancing and retracting the brush, a polish carrying box, movably mounted in the path of the brush and normally supported with the surface of the polish therein in ad-

vance of the periphery of the brush when in its retracted position.

19. A shoe shining machine, having in combination a polish applying brush, a carrier therefor, mechanism for advancing and retracting the brush carrier, a polish carrying box suspended independently of the brush carrier back of and in the path of the brush whereby the brush engages the box when in its retracted position and is disengaged from the box in its advanced position.

20. A shoe shining machine, having in combination a rotary polish applying brush, mechanism for advancing and retracting the

brush, a segmental polish carrying box arranged to embrace the rear portion of the periphery of the brush when in retracted position, and a frame in which the box is carried mounted to swing away from the brush during the advance movement of the brush.

In witness whereof, we have hereunto set our hands, this 20th day of October 1906.

ERNEST F. SYMONDS.
GEORGE W. BRANN.

In the presence of—

IRA L. FISH,
KATHARINE A. DUGAN.
